SURFACE SMOOTHNESS TESTER

Hermann Kott, East Orange, N. J., assignor to
Alco-Gravure Division of Publication Corpora-
tion, New York, N. Y., a corporation of New
York

Application March 10, 1938, Serial No. 195,059

13 Claims. (Cl. 88—14)

This invention relates to the determination of relative smoothness characteristics of surfaces, and has particular reference to an improved method of testing the smoothness characteristics of paper surfaces, and apparatus for accomplishing the same.

In the printing art, the quality of the printed product obtained is dependent to a great extent on the smoothness of the paper used in the printing process. By smoothness is meant the evenness or lack of roughness of the paper. A smooth paper is usually characterized by an even surface, which, if examined closely, appears to be closely dotted with numerous tiny projections. In a rough paper, these projections are relatively large, and are not so closely spaced as in a smooth paper so that the paper has a rough or coarse texture which can be readily felt when the fingers are rubbed over it.

In accordance with current practice, the pressure of the printing rolls is adjusted at the beginning of a run to give the desired tone on the paper and is not changed thereafter. So long as the smoothness of the paper remains the same, a uniform product obtains, and no further adjustment of the pressure on the printing rolls is necessary. If, however, the smoothness of the paper changes, as might occur where a number of rolls of paper are used successively, it has been found that the copies printed from the successive rolls do not have the same tone as those which were printed before. For example, where the paper in the second roll is not so smooth as that previously used, it will be found that the boundaries between differently colored portions of the printed matter are not as sharply defined as before. Furthermore, delicate tints, especially the flesh colors or light blues, are found to be considerably darker in tone on the rougher paper.

This results from the fact that the ink from the plates is applied only to the tips of the projections on the paper surface, and since in a rough paper the effective area in contact with the printing cylinder per unit area of paper is less than in a smooth paper, the ink density is much greater than it would be on a smoother paper and consequently, the tones are darker. The projections on the paper surface, moreover, are spread out to a considerable extent so that a great many unprinted portions exist between them, thus causing the poor definition noted.

This condition may be compensated for by adjusting the pressure of the printing rolls, but it frequently happens that the change in the qual-

ity of the printed product is not immediately noted so that a great many copies of poor quality are run off before any adjustment is made. In order to make the adjustment, furthermore, the press must be shut down and a number of test runs made to obtain the desired tone so that an undesirable and costly delay results.

The present invention provides an apparatus for measuring the relative smoothness of various paper surfaces, which can be used to determine the relative smoothness of the printing paper rolls before they are put into the press. The relation between the relative smoothness of the paper and the printing roll pressure necessary to obtain a product of required definition, and tone may be easily obtained by conducting a number of simple tests. Knowing this relation and the relative smoothness of the paper, a printed product of the desired definition and tone can always be obtained, and the disadvantages of the present hit-or-miss system avoided.

An object of this invention accordingly is to provide a simple apparatus for measuring the relative smoothness of paper surfaces.

25 Another object of the invention is to provide an improved method and apparatus for measuring relative smoothness in which the smoothness of an unknown surface is measured in terms of its ability to reflect light after an ink impression of standard pressure has been made on it.

Another object of the invention is to provide an apparatus of the above character wherein the smoothness of a paper surface is tested 35 photoelectrically.

Another object of the invention is to provide an apparatus of the above character in which the smoothness of the paper surface is determined by a null measurement.

40 In a preferred embodiment of the invention two beams of substantially identical intensity are directed from a constant source of light upon the opposite faces of the sample to be tested, and the light reflected from the surfaces of the

45 test object is then directed to a photoelectric cell. The two light beams originating from the source are alternately interrupted in such fashion that the rays falling on the photoelectric cell from each beam vary sinusoidally with time and 50 are 180° out of phase, so that equal areas of the photoelectric cell are illuminated alternately. One side of the surface to be tested is smudged with ink so that it appears darker than the clean surface, the degree of darkness depending directly on its smoothness. The light now reflect-

ed from the smudged surface is considerably less than that reflected from the clean surface, thus producing an alternating current in the circuit of the photoelectric cell. The alternating current is then amplified in a special balanced amplifier until it is of sufficient magnitude to operate an indicating meter.

The beam of light which is directed on the clean side of the test surface is now reduced in area by means of an iris diaphragm until the reading of the indicating meter is brought to zero, at which point the beams of light reflected from the smudged surface and the clean surface are equal. The relative smoothness of the surface may then be read directly from the iris diaphragm which may be suitably calibrated to read percentage smoothness.

Since a null method is used in which the readings do not depend upon the indication of the meter in the amplifier circuit, the determinations made will be independent of errors due to any non-linearity in the response of the photocell or the amplifier circuit itself.

The invention may be better understood from the following detailed description and the accompanying drawing; in which:

Figure 1 is an apparatus for testing the smoothness of paper surfaces, constructed in accordance with this invention.

Figure 2 is a partial view of an apertured disc which may be used to interrupt the light beams of the smoothness tester; and

Figure 3 is a schematic diagram of a circuit which may be used to amplify the impulses from the photoelectric cell.

Referring to Figure 1, a light source of substantially constant intensity is shown at 10, from which light is directed through condensing lenses 11 in an elongated cylindrical tube 12 to form light beams therein. Light also passes from the source 10 to a prism 13 which serves to direct light through the condensing lenses 14 to provide light beams in the elongated cylindrical tube 15 which is disposed parallel and adjacent to the tube 12. In front of the tubes 12 and 15 a circular disc 16 is located, in which the staggered apertures 17 and 18 are formed. These apertures are so disposed that when the apertures 17 permit the passage of light from the tube 15, the passage of light from the tube 12 is prevented, and vice versa.

A second pair of tubes 19 and 20 are mounted on the other side of the disc 16 coaxially, respectively, with the tubes 12 and 15. The tubes 19 and 20 are provided with lenses 21 and 22, respectively, which serve to focus light upon the prisms 23 and 24, respectively, from which light is reflected through the lenses 25 and 26, respectively, to the faces 27 and 28 of the test surface 29 which is disposed between the two systems and parallel thereto. The light reflected from the face 27 is directed through a lens 30 and prisms 31, 32 and 33 and through a diaphragm 34 to the surface of a photoelectric cell 35 and the light reflected from the face 28 is directed through a lens 36, prisms 37, 38 and 39 and through the diaphragm 34 to the surface of the photoelectric cell 35.

The apertures 17 and 18 in the disc 16 are so spaced that as the disc is rotated the light is cut off from an aperture 17 at the same instant that light begins to pass through the adjacent aperture 18. As the disc 16 rotates, it is evident that the quantity of light passing through each of the tubes varies sinusoidally with time, and the beams

are 180° out of phase, so that if the two sides 27 and 28 have the same degree of smoothness, a constant amount of light will fall on the photoelectric cell and a direct current will pass through its circuit.

Referring to Figure 3, a balanced amplifier circuit is shown for amplifying current impulses from the photoelectric cell which is of a well known type and therefore need be described only briefly. The photoelectric cell current impulses pass through a wire 36, and the blocking condenser 74, to a grid resistor 75 across which an alternating voltage appears which is impressed on an amplifying tube 76. The amplified voltage is developed across the plate resistor 40 and is then impressed on the grid resistor 41 through a blocking condenser 42, so that the amplified voltage is applied to the grid of a second tube 43. The indication is made by a meter 44 which is placed across the plate and screen grid leads of the tube 43 and which can be adjusted to a zero position by means of the variable resistors 46 and 47 in series with the plate and screen grid, respectively.

The power for the amplifier is supplied from step-up transformer 48 which provides a source of high voltage alternating current. This voltage is rectified by the electronic rectifier 49 and is thereafter filtered in a two-section filter comprising the reactor 50 and a variable resistor 51 in series, and the condensers 52, 53 and 54 in parallel. This two-section filter filters out the alternating components of the pulsating direct current delivered by the rectifier 49, so that a substantially constant direct voltage is obtained at the output which is then impressed on a voltage regulator tube 55 of a well known type. Thus a substantially constant voltage is supplied through the wire 56 to the screen grid and plate of the tube 43 through the variable resistors 47 and 46, respectively. The same wire also delivers voltage to the plate of the amplifying tube 76 through the plate resistor 40 and a single section filter comprising the series resistor 57 and shunt condenser 58.

Voltage is also supplied to the screen grid of the tube 76 through a voltage dropping resistor 62 and a single section filter comprising a series resistance 60 and shunt condenser 61. The same wire also supplies voltage through a voltage dropping resistor 63 for polarizing the photoelectric cell 35. The voltage dropping resistor 63 and the photoelectric cell 35 are shunted by a condenser 64 which serves to provide a low reactance bypass for any alternating current components which may still be present in the direct current supply.

Voltage for biasing the grid of the amplifying tube 76 is provided by variable resistor 65 across which part of the output of the voltage regulator tube 55 is impressed. The biasing voltage for the grid of the tube 43 is similarly supplied by means of a variable resistor 66 which is connected in parallel with the resistance 65. The resistances 65 and 66 are shunted to ground by the bypass condensers 67 and 68, respectively, which tend to prevent undesirable degenerative effects and also provide a low reactance path for any alternating components which may be present in the direct current supply. Additional filtering is provided by the condenser 69 which is connected across the output of the voltage regulator tube 55 so that a direct current voltage is obtained at its terminals which has substantially no alternating current ripple.

The meter which is connected across the screen

grid and plate terminals of the tube 43 is adjusted to give a zero reading when both light beams are of the same intensity, the adjustment being made by the variable resistors 46 and 47. This amplifier is well known for its stable and unvarying characteristics, a feature which makes it very suitable for amplifying photocell impulses of small magnitude.

In an actual test, one side of the test piece 29, for example, the side 27, is placed beneath an ink stencil to which a fixed pressure is applied so that its surface is smudged with ink. It is then put in the testing apparatus in the position shown in Figure 1, so that less light is reflected from the surface 27 than from the surface 28. Under these conditions, there are two sinusoidally varying beams of light falling on the photoelectric cell which are 180° out of phase, one of which is of greater intensity than the other. As a result of the change in the light reflected from the two surfaces, the total light falling on the photoelectric cell varies sinusoidally with time, so that an alternating current flows in the circuit of the photoelectric cell 35. This alternating current is amplified by the amplifier described above, causing the meter 44 to give a positive indication which may be used as a measure of the relative smoothness of the paper, if desired. It is preferred, however, to reduce the area of the beam of light directed on the clean surface 28 by operating an iris diaphragm 13, until the reading of the meter 44 is reduced to zero. The relative smoothness of the paper may then be directly read from markings on the diaphragm 13 which can be calibrated to read a measure of smoothness directly. The advantage of the latter null method of measurement is that it is independent of errors which might be introduced due to non-linearity of the photocell or its amplifier, or errors in the indicating meter.

It is evident from the foregoing that the invention provides an improved apparatus by means of which the smoothness of a paper surface may be readily determined and paper samples of varying degrees of smoothness may be easily and effectively compared. An important feature of the invention is that all determinations are made by a null measurement so that no errors are introduced due to non-linearity of the photoelectric cell or the amplifying system.

The embodiments and methods described above are obviously capable of numerous changes in form and detail within the scope of the invention and it is not intended to be in any way limited thereby except as defined in the appended claims.

I claim:

1. The method of measuring the relative smoothness of the surfaces of a specimen, comprising smudging one face of a specimen with ink at a predetermined pressure, directing a beam of light from a source to the smudged face, directing a second beam of light from the same source to the clean face, alternately interrupting the said light beams, directing the light reflected from both said faces to a photosensitive device to produce current impulses therein ranging in magnitude from zero when the reflected light beams are of equal intensity to a maximum when the beams are of maximum inequality in intensity, and comparing the magnitude of the current impulses with a standard magnitude to

determine the relative smoothness of the faces of said specimen.

2. The method of measuring the relative smoothness of the surfaces of a specimen, comprising smudging one face of a specimen with ink at a predetermined pressure, directing a beam of light from a source to the smudged face, directing a second beam of light from the same source to the clean face, adjusting the intensities of the light beams reflected from said surfaces to a predetermined relation and comparing the adjustment with a standard adjustment to measure the smoothness of the faces of said specimen.

15 3. The method of measuring the relative smoothness of the surfaces of a specimen, comprising smudging one face of a specimen with ink at a predetermined pressure, directing a beam of light from a source to the smudged face, 20 directing a second beam of light from the same source to the clean face, interrupting the said light beams alternately, directing the light reflected from both said faces to a photosensitive device to produce current impulses therein, amplifying the said photosensitive device current impulses, determining the magnitude of the said amplified current impulses adjusting the intensity of at least one light beam until the current impulses are of a predetermined magnitude, and 25 comparing the adjustment of said light beam with a standard adjustment to determine the relative smoothness of the faces of said specimen.

4. The method of measuring the relative smoothness of the surfaces of a specimen, comprising smudging one face of a specimen with ink at a predetermined pressure, directing a beam of light from a source to the smudged face, directing a second beam of light from the same source to the clean face, interrupting the said light beams alternately, directing the light reflected from both said faces to a photosensitive device to produce current impulses therein, amplifying the said photosensitive device current impulses, measuring the magnitude of the said amplified current impulses, adjusting the cross sectional area of at least one of the said light beams to reduce the measured current impulses to a predetermined value and comparing 50 the adjustment of the area of said light beam with a standard adjustment to determine the smoothness of said faces.

5. An apparatus for identifying the smoothness characteristic of paper surfaces comprising a light source, means to direct a beam of light from the light source to one surface of the paper, means to direct a second beam of light from the light source to the opposite surface of the said paper, means for varying the said light beams sinusoidally with time and in opposite phase relationship, means responsive to the differences in the intensities of light beams for indicating differences in the intensities of the light beams reflected from the said surfaces, means for equalizing the intensities of the reflected light beams, and means calibrated in degrees of relative smoothness actuated with said equalizing means for indicating the smoothness of the said paper surfaces when the intensities of the light beams are equal.

6. A device for measuring the relative smoothness of paper surfaces comprising a light source, means to direct a beam of light from the light source to one surface of the said paper, means to direct a second beam of light from the light

source to the opposite surface of the said paper, means for varying the said light beams sinusoidally with time and in opposite phase relationship, means responsive to differences in the intensities of light beams for indicating differences in the intensities of the said light beams reflected from the said surfaces, means for equalizing the intensities of the said reflected light beams by adjusting the cross-sectional area of at least one of said beams, and means calibrated to indicate variations in smoothness actuated with said equalizing means for indicating the smoothness of said paper surfaces when the intensities of the light beams are equal.

7. A device for measuring the relative smoothness of surfaces of a specimen, comprising a light source, means to direct a beam of light from the light source to one face of the specimen, means to direct a second beam of light from the light source to another face of the said specimen, means for varying said beams in opposite phase relationship, means responsive to differences in the intensities of the light beams reflected from the said faces for indicating the variations in the relative intensities of the reflected light beams caused by variations in the reflecting power of the said specimen faces.

8. A device for measuring the relative smoothness of surfaces of a specimen, comprising a light source, means to direct a beam of light from the light source to one face of the specimen, means to direct a second beam of light from the light source to another face of the said specimen, means for varying said beams in opposite phase relationship, photosensitive means responsive to differences in the intensities of beams of light reflected from said surfaces, means controlled by said photosensitive means for indicating variations in relative intensities of the reflected light beams caused by variations in the reflecting power of said surfaces and means for equalizing the intensities of said reflected light beams said equalizing means being calibrated in terms of smoothness of the specimen faces.

9. A device for measuring the relative smoothness of surfaces of a specimen, comprising a light source, means to direct a beam of light from the light source to one face of the specimen, means to direct a second beam of light from the light source to another face of the said specimen, means to vary the said beams substantially sinusoidally with time and in opposite phase relationship, a photosensitive cell responsive to the light beams reflected from the said specimen faces and means actuated by said photosensitive cell for indicating unequal energization of the said cell by said beams.

10. A device for measuring the relative smoothness of surfaces of a specimen, comprising a light source, means to direct a beam of light from the light source to one face of the specimen, means to direct a second beam of light from the light source to another face of the said specimen, means

to vary the said beams substantially sinusoidally with time and in opposite phase relationship, a photosensitive cell responsive to light beams reflected from the said specimen faces, means actuated by said photosensitive cell for indicating unequal energization of the said cell by the said beams, and means for adjusting the area of at least one of the said light beams to equalize the reflected intensities thereof, said adjusting means being calibrated to indicate variations in smoothness.

11. A device for measuring the relative smoothness of surfaces of a specimen, comprising a light source, means to direct a beam of light from the light source to one surface of the specimen, means to direct a second beam of light from the light source to another surface of the specimen, a rotatable disk, having apertures formed therein in the respective paths of the said light beams, the apertures in each path being staggered with respect to the apertures in the other path, means for rotating the disk to vary the beams sinusoidally with time and in opposite phase relationship, means to direct the light beams reflected from the said surfaces to a photosensitive cell, and means actuated by said photosensitive cell for indicating variations in the relative intensities of the light beams reflected by said surfaces.

12. A device for measuring the relative smoothness of surfaces of a specimen, comprising a light source, means to direct a beam of light from the light source to one surface of the specimen, means to direct a second beam of light from the light source to the opposite surface of the specimen, a rotatable apertured disk for interrupting the said light beams alternately, means to direct light reflected from both of said surfaces to a photosensitive cell, means actuated by said cell for indicating unequal intensities of the reflected beams and an iris diaphragm for adjusting the cross-sectional area of one of the said beams to equalize the intensities of the reflected beams.

13. A device for measuring the relative smoothness of specimen surfaces, comprising a light source, means to direct a beam of light from the light source to one surface of the specimen, means to direct a second beam of light from the light source to the opposite surface of the said specimen, a rotatable apertured disk for interrupting the said light beams alternately, means for rotating said disk, reflecting means to direct light reflected from both said surfaces to a photosensitive cell, means to amplify the impulses from the said photosensitive cell, means in the circuit of the amplifying means for indicating unequal intensities of the beams reflected from said surfaces, an iris diaphragm for varying the cross-sectional area of one of the said light beams to equalize their reflected intensities and a scale on said diaphragm for indicating the smoothness of a surface of said specimen.

HERMANN KOTT.
